CLAIM

The ornamental design for a stacked air fryer, as shown and described.

DESCRIPTION

FIG. 1 is a front perspective view of a first embodiment of our stacked air fryer;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof; and,
FIG. 8 is a bottom perspective view thereof.

In some embodiments, the stacked air fryer, as shown in FIGS. 1-8, includes a slanted handle on a front portion of each air fryer compartment, in the center of two similar parallel rectangular features.

The broken lines shown in the figures show features of the stacked air fryer that form no part of the claimed design.
